US00D589496S

(12) **United States Design Patent**
Legrand

(10) **Patent No.:** **US D589,496 S**
(45) **Date of Patent:** **** Mar. 31, 2009**

(54) **REMOTE CONTROL DEVICE**

(75) Inventor: **Raphaëlle Legrand**, Antony (FR)

(73) Assignee: **Archos**, Igny (FR)

(**) Term: **14 Years**

(21) Appl. No.: **29/290,523**

(22) Filed: **Dec. 13, 2007**

(30) **Foreign Application Priority Data**

Jun. 13, 2007 (FR) 07 2730

(51) **LOC (9) Cl.** **14-03**

(52) **U.S. Cl.** **D14/218**
